UNITED STATES PATENT OFFICE.

JOHN J. LALLY, OF SYRACUSE, NEW YORK.

SCRUB-BRUSH.

1,329,416.

Specification of Letters Patent.

Patented Feb. 3, 1920.

Application filed January 2, 1918. Serial No. 209,812.

To all whom it may concern:

Be it known that I, JOHN J. LALLY, a citizen of the United States, residing at Syracuse, in the county of Onondaga and 5 State of New York, have invented certain new and useful Improvements in Scrub-Brushes, of which the following is a specification.

This invention relates to improvements in 10 scrubbing brushes, and has for its particular object to provide a brush of the class, which is especially adapted and intended for scrubbing walls and like surfaces. A further object is to provide a simple and convenient handle which is pivotally connected 15 to the back of the common scrub-brushes, and may be detached when a brush is worn out and applied to a new brush. A further object is to so apply the handle to the back 20 of the brush that when applied to a wall or other vertical surface the brush, acting under the influence of gravity, readily assumes the proper position, substantially parallel to the wall, for facilitating the scrubbing or 25 cleaning of the wall. And a further object is to generally improve and simplify the construction and operation of brush holders.

I attain these objects by the means set forth in the detailed description which follows, and as illustrated by the accompanying drawing, in which—

Figure 1 is a perspective view; showing a portion of a brick-wall, to which my improved scrubbing device is applied.

Fig. 2 is a side elevation, with parts of the brush and handle broken away; showing the construction and arrangement of the various parts.

It has long been the custom to paint brick 40 and stone walls, so as to protect them and improve their appearance, and in carrying out this work, such walls are invariably scrubbed or otherwise cleansed and put in condition to receive the paint or other dressing. Ordinarily to clean brick or stone 45 walls, the cleaners dash a quantity of acid, usually muriatic acid, over the surface of the wall, then they dash water over the acid covered surface, after which, the operators, by means of common scrubbing 50 brushes scour and cleanse the walls. Heretofore, as a rule, the brushes employed for this scrubbing work have been plain and the operators held them in their hands while 55 doing the scrubbing work. This resulted in more or less of the acid coming in contact

with the operators' hands and also spattering over their clothes and burning and injuring the same. To remedy these defects and to prevent the said injuries, I have devised a novel and simple handle attachment, which enables the operator to do his work more readily and with greater ease and safety, because he can keep at a safe distance from the acid covered walls while doing the scrubbing work. A detailed description of my invention follows:

In the drawing, 2 represents a scrubbing brush of conventional form, having a substantial back 3, and the usual bristles 4. 70 Scrub-brushes of the class are generally made with wooden backs and in many different forms and sizes, but as a rule they have a greater length than breadth, as shown. My improvement consists of a handle 5, which 75 may be made of wood, the lower end thereof being inserted in the upper end 6 of a socket-holder 7, which is preferably made of sheet metal. The lower end 8 of the holder is flattened and fan-shaped. The 80 handle is preferably held in place by rivets 9, which pass through the handle and holder, as shown in Fig. 2. The fan-shaped end 8 of the holder is provided with similar spaced hinge-loops 10, which straddle and 85 receive a single loop 11, the latter being an integral part of a second hinge-member 12, which is suitably secured to the top-face of the back 3 by screws 13. A pintle or pin 14 is then driven through the loops 10—11 90 for completing the hinge structure. In applying the member 12 to the back 3 of the brush, the said member is preferably disposed forwardly of the middle of the back 3, as shown, so that when the brush is lifted 95 up by the handle and brought into contact with a wall, as 15, the brush gravitates to the proper position parallel to the wall. Thereafter, as the handle 5 is manipulated for moving the brush upwardly and downwardly, over the wall, the brush retains its proper position, as shown in Fig. 1, throughout the scrubbing operation. Owing to the broad hinge structure, which extends substantially the full width of the back 3, the 100 brush may also be moved laterally as well as vertically over the wall-surface, or it may be given a rotary motion, without danger of breaking or injuring the hinge connections.

Obviously, a brush equipped with my improved hinge and handle may be used for scrubbing floors and other surfaces, as 110

shown in Fig. 2, wherein the full and dotted lines indicate that the brush may be operated in either direction at will.

Having thus described my invention, 5 what I claim as new and desire to secure by Letters Patent, is—

1. The combination with a brush having a solid elongated back, of a stationary hinge member secured to and extending transversely of the back near one end thereof and provided with a pintle loop, a movable hinge member having one end thereof formed with a substantially cylindrical ferrule and its other end flattened and of substantially the 15 same width as the width of the brush back and extending transversely of said brush back, said flattened end being cut away to form spaced pintle loops of the same size as and disposed on opposite sides of the pintle 20 loop of the stationary member and in the same plane therewith, a pintle pin extending through all of said loops, a handle fitted in the ferrule and terminating short of the flattened end of the hinge member, and a rivet extending through the flattened portion 25 of the movable hinge member between the cut away portion thereof and the end of said handle.

2. The combination with a brush having

an elongated back, of a stationary hinge member secured to and extending transversely of the back near one end thereof and having a transverse pintle loop lying at one side against the face of the back, a handle having its attached end 35 tapered, a movable hinge member having one end thereof provided with a tapered ferrule disposed in longitudinal alinement with and receiving the tapered end of the handle and its other end flattened and extending transversely of the back for substantially the entire width of said back and provided with spaced pintle loops fitting on opposite sides of the pintle loop of the stationary hinge member and in the same 40 plane therewith, and a transverse pintle pin fitting through said loops and connecting the movable hinge member with the stationary hinge member upon the brush back for free pivotal movement in an arc terminating at its ends substantially at the plane of the face of the back of the brush, whereby in one extreme position of swinging movement of the handle the same may extend substantially parallel to said plane. 50

In testimony whereof I affix my signature. 55

JOHN J. LALLY.
